WATCHMAKER'S HAND CLAMPING TOOL

Oscar A. Bettum, Washington, D. C.

Application November 13, 1947, Serial No. 785,759

5 Claims. (Cl. 81—6)

1

This invention relates to a watchmaker's combination tool or clamp.

The invention is more particularly concerned with a tool in the form of a combination watch parts supporting, positioning and clamping device wherein practically all of the cooperating parts of a watch may be dis-assembled, repaired and assembled.

In the watch repairing art, it is highly important that the parts, and particularly the smaller and more delicate parts be kept from contact with the workman's hands and it is equally important that the parts be supported or rigidly held in a position wherein they are clearly visible for operation thereon:

It is accordingly a primary object of this invention to provide a watchmaker's tool for the support and retention of the various watch parts whereby they are clearly visible and are retained for operation thereon without being touched by the hands of a workman.

A further object of the invention is to provide a watchmaker's tool embodying supporting and positioning means for individual watch parts, and a yieldable clamp for retaining any of such parts in its supported position.

A still further object of the invention is to provide a watchmaker's tool embodying a support for different watch parts, a clamp plate for engaging any one of several parts, spring means for yieldably urging the clamp plate against the part, and the spring means including a pin extending through the clamp plate and adapted to yieldably engage a part supported beneath the plate or to extend into an aperture therein to aid in maintaining the part in position.

Other objects and advantages of the invention will become apparent in the course of the following description, taken in connection with the accompanying drawing, wherein:

Fig. 1 is a perspective view of the improved device, and which with Figs. 2 to 7 inclusive is on a substantially enlarged scale.

Fig. 2 is a bottom plan view of the device.

Fig. 3 is a top plan view showing a balance wheel being supported thereby.

Fig. 4 is a broken fragmental plane view, partially in section, to show the clamping plate actuating spring mounting which urges the forward work engaging and securing edge portion of the clamping plate toward the work supporting and positioning surface of the base plate.

Fig. 5 is a side elevational view of the device.

Fig. 6 is a longitudinal vertical section in the plane of line 6—6 on Fig. 3.

5

2

Fig. 7 is a rear elevational view.

Fig. 8 is a top plan view showing the device as of actual size and the figure bearing indicia to indicate some of the many uses of the device.

Fig. 9 is a transverse sectional view taken on line 9—9 of Fig. 4, to further show the combination clamping, positioning and securing action of forward edge and corner portions of the clamping plate and adjacent perforated and longitudinal edge or shoulder portions of the base plate on a watch part to be worked upon.

Referring now in detail to the drawing, 10 designates a base plate which is constructed from relatively heavy sheet material, such as brass or other suitable metal or non-metal.

The base is of generally elongated rectangular form and is provided with front supporting legs 11 and rear supporting legs 12, and which legs are preferably bent from the material forming the base as is illustrated.

The base is further provided with a supporting leg 13 intermediate the front and rear legs 11 and 12 and such leg is preferably bent down from the base at the rear edge of a relatively large opening 14 which functions in a manner later set forth.

The base plate 10 is provided adjacent its front end with a relatively large aperture 15, a somewhat smaller aperture 16, a pair of similar and still smaller apertures 17 and 18 and a very small aperture 19. The base plate is further provided with a relatively large aperture 20 adjacent its rear end and a pair of laterally aligned apertures 21 adjacent its front end.

The base plate is provided with a pair of laterally aligned lugs 22 which are rigid with the plate and receive the opposite ends of a pivot pin 23 which also extends through a pair of lugs 24 rigid with and depending from a clamp plate 25 and the lugs 24 are disposed between and adjacent to the lugs 22 as is more clearly indicated in Fig. 7.

The clamp plate 25 which is formed from relatively light gauge sheet material is of a width substantially equal to that of the base plate and provided with a straight front edge extending normal to the side edges or shoulders 10' and is preferably provided with an upwardly curved rear end as illustrated for substantial conformity with a finger used for depressing such end in the operation of the clamp.

The clamp plate is provided with a pair of slots 26 and said clamp plate is yieldably urged with its front edge normally engaged with the base plate at a point substantially rearwardly of

the front end of the base plate and adjacent the apertures 15 to 19, by means of a spring including relatively long leg portions 27 and 28 which extend from beneath the plate, through the slots 26 and thence downwardly through apertures in the plate adjacent the front edge thereof. The legs 27, 28 include terminal portions 27', 28' in the form of pins and which are the portions extending downwardly through the apertures in the plate substantially normal thereto, and these pins normally extend into the apertures 21 in the base plate 10.

The leg portions 27 and 28 extend as continuations of coils 29 and 30 respectively and which surround the pivot pin 23 intermediate and adjacent the respective lugs 24 on the clamp plate.

The leg portions 27 and 28 project from the opposite ends of the coils and the coils of their adjacent ends are interconnected by an elongated U-shaped portion 31 which bears on the base plate 10.

As before noted, the front edge of the clamp plate 25 normally bears on the base plate 10 rearwardly of the apertures 15 to 19 in a line transverse of the base plate and the latter is provided with opposite side edges 32 in advance of said line which are slightly depressed with respect to the top surface of the remainder of the base plate in the provision of additional side edges or shoulders 32' for a purpose later set forth. In Figs. 4 and 9, a watch part similar to that shown on reverse side in Fig. 1, is illustrated in positioned and clamped condition upon the base plate 10, with the bearing mounting held directly over the aperture 15 for removing or replacing the jewel and for setting the regulator hand on the arbor surrounding the bearing etc. In this view it will be noted how the several tool parts i. e. the apertured base plate 10, having longitudinal side edges 32-32' support and direct watch parts which are clamped and secured thereon by the forward edge and corner portions of the spring pressed clamping plate 25.

The function of the various co-operating parts as above described is in part indicated in Fig. 8 wherein it will be noted that the apertures 15 to 18 are for the purpose of receiving the hubs of different sizes of balance wheels in the operation of removing or adjusting the hair spring.

These apertures are thus of different sizes to accommodate different size balance wheels.

In Fig. 3 a balance wheel W is shown supported in aperture 15 with the clamp plate 25 engaging a portion of the perimeter of the wheel.

The balance wheel as here shown is positioned and held for assembly of the hair spring thereon and it will be seen that practically the entire wheel is visible whereby materially facilitating the delicate operation of assembling the hair spring.

The edges 32 and shoulders 32' are for the purpose of supporting the balance wheel bridge, one for the right and the other for the left as indicated in Fig. 8.

In Fig. 1 a bridge 3 is shown and wherein the hub portion (more clearly shown in Fig. 6) engages a shoulder 32' while a major portion of the bridge rests on the plate 10 proper.

As indicated in Fig. 1 the pin or end portion 27' of the spring extends into an aperture in the bridge which together with the shoulder 32' maintains the bridge in rigid position laterally of the tool and the pressure of the clamping plate 25 on the bridge retains it in such position.

Also as indicated in Fig. 8 the forward edge of the clamp plate 25 in cooperation with the base

plate 10 retains any part of a watch for jewel set or repair.

The small aperture 19 as indicated in Fig. 8 is for the purpose of adjusting pallet spans and the relatively large aperture 20 is for the purpose of receiving the projecting side portion of the main spring casing for properly supporting same on the anvil surface of the base plate 10, relative to the rear clamping edge of the pivoted thumb plate 25 in forceably applying the barrel cover on the main spring casing. The various apertures and surfaces as above noted are so positioned and arranged with respect to clamping edge portion of the clamp plate 25 as to properly and rigidly support and retain other watch parts not herein specifically referred to.

In Fig. 5 is illustrated a bridge 3 wherein the spring urged pin 27' engages a surface thereof rather than enter an aperture therein as in Fig. 20 and such pin 27' together with the adjacent cooperating edge of the clamp plate 25 holds the bridge firmly in position for any operation thereon such as the mounting of the balance wheel.

In Fig. 6 a bridge 3 is shown wherein a portion 25 thereof projects into the opening 14 in the base plate 10 and which opening is for the purpose of receiving projecting portions of watch parts when supported for a particular operation thereon.

It is to be noted that the base plate 10 finds 30 firm support on the opposite end legs 11 and 12 together with the intermediate leg 13 and that all of the watch parts supporting and locating elements are unitary with the base plate whereby the watch parts will always be accurately supported in the proper and desired position and since the clamp plate is pivotally connected to the base plate it will always cooperate with the supporting elements for easy and accurate operation on any of the many different watch parts.

As before stated the spring arms 27 and 28 40 yieldably urge the clamp plate to a normal position wherein its front edge has line contact with the base plate rearwardly of but adjacent to the apertures 15 to 19 as well as the supporting edges 32 and shoulders 32'. Furthermore, the spring arms 27 and 28 are individually yieldable independently of the clamp plate.

With this arrangement, the clamp plate acts to retain parts in position through the yieldable arms as is indicated in connection with the balance wheel in Fig. 3. Furthermore either of the spring arms may exert its own pressure directly on a part as in Fig. 5 while the other spring arm exerts its influence on the clamp plate and which therethrough is transferred to the said part for cooperative clamping action thereon.

Furthermore, the pin or terminal end portion of one of the arms may act to hold a part against sidewise movement as in Fig. 1 while both arms 60 exert their influence on the clamp plate, and a part may be engaged by both terminal ends 27', 28' in which event the plate 25 will have no bearing pressure thereon.

The improved tool may be briefly summarized as comprising a plurality of watch parts supporting and positioning means, and clamp means co-operating therewith for the retention of any one of the many watch parts for most effective operation thereon as may be required in the repair operation on a watch.

It is to be particularly observed that the tool is very simple in construction whereby adapting it for manufacture at relatively low cost and that 75 the tool as disclosed is highly efficient in the sup-

port and retention of any watch part on which an operation is to be performed.

While I have disclosed my invention in accordance with a single specific embodiment thereof, such is to be considered as illustrative only, and not instructive, the scope of the invention being defined in the subjoined claims.

What I claim and desire to secure by U. S. Letters Patent is:

1. A watchmaker's tool comprising an elongated generally rectangular base plate provided with supporting legs, a generally rectangular clamp plate disposed above the base plate with its forward edge spaced inwardly from the corresponding edge of the base plate and of substantially the same width thereof, cooperating lugs rigid with said plates intermediate their ends and adjacent the opposite sides thereof, a pivot pin extending through said lugs providing a transverse pivotal connection between the plates, spring means operatively engaged with said plates for normally urging one end of the clamp plate into contact with the base plate in a line transverse thereof and in spaced relation to the front end thereof, and watch parts positioning and supporting means on said base plate between said contact line and said front end and from one edge to the other thereof and in operative association with both aligning side edges and the entire length of said one end of the clamping plate.

2. A tool according to claim 1 wherein said clamp plate is provided with a pair of laterally spaced longitudinal slots disposed intermediate said one end thereof and said pivot pin, an aperture in said clamp plate adjacent said one end at each side thereof in alignment with a respective one of said slots, said spring means including a pair of relatively long arms extending upwardly from said pivot pin, through said slots and including vertically disposed end portions extending downwardly through said apertures, and apertures in said base plate receiving said end portions in the normal position of the clamp plate.

3. A watchmaker's tool comprising an elongated generally rectangular base plate, a generally rectangular clamp plate shorter than the base plate and of substantially the same width thereof,

said clamp plate being disposed above the base plate and pivotally connected thereto intermediate the ends of the plates, spring means supported above the base plate and including intermediate coil portions, a loop portion bearing on the base plate, and elongated arm portions operatively engaged with the clamp plate for urging one end thereof toward the base plate, and said arm portions including vertically disposed terminal pin portions vertically movable relative to the clamp plate and providing clamping members extending between the plates.

4. A watchmaker's tool comprising an elongated generally rectangular base plate, a generally rectangular clamp plate shorter than the base plate and of substantially the same width thereof, said clamp plate being disposed above and spring pressed toward the base plate and pivotally connected thereto intermediate the ends of the plates, said clamp plate having a straight clamping edge extending normal to the side edges of the base plate and inwardly of the front edge of the base plate to provide a right angular clamping corner on the clamp plate adjacent each said side edge, and cooperating aligned watch parts engaging and positioning means in each said corner and the subjacent portions of the base plate.

5. A tool according to claim 4, together with watch parts positioning means on the base plate intermediate said side edges in operative association with portions of said clamping edge between the corners thereof.

OSCAR A. BETTUM.
